Specification for Design.

Patented Jan. 3, 1922.

Application filed May 28, 1921. Serial No. 473,415. Term of patent 14 years.

To all whom it may concern:

Be it known that I, MAGNOLIA B. LYTLE, a citizen of the United States, residing at Nashville, in the county of Davidson and State of Tennessee, have invented a new, original, and ornamental Design for a Stand for an Electric Iron, of which the following is a specification, reference being had therein to the accompanying drawings.

Figure 1 is a perspective view of a stand for an electric iron, showing my new design.

Figure 2 is a view along line 2—2, Fig. 1.

What I claim is:

The ornamental design for a stand for an electric iron, as shown.

In testimony whereof I hereunto affix my signature.

MAGNOLIA B. LYTLE.
